US00D455735S

(12) **United States Design Patent** (10) Patent No.: **US D455,735 S**
Winslow (45) Date of Patent: ** Apr. 16, 2002

(54) **SUBSCRIBER PREMISES TRANSCEIVER
FOR A LOCAL MULTI-POINT
DISTRIBUTION SERVICE**

(75) Inventor: **George D. Winslow**, Greenfield, MA (US)

(73) Assignee: **Telaxis Communications Corporation**, South Deerfield, MA (US)

(**) Term: **14 Years**

(21) Appl. No.: **29/138,359**

(22) Filed: **Mar. 12, 2001**

Related U.S. Application Data

(63) Continuation of application No. 29/116,392, filed on Dec. 30, 1999, now abandoned.

(51) **LOC (7) Cl. 14-03**

(52) **U.S. Cl. D14/240; D14/358**

(57) **CLAIM**

The ornamental design for a subscriber premises transceiver for a local multi-point distribution service, as shown and described.

DESCRIPTION

FIG. 1 is a front isometric view of a transceiver according to the invention.

FIG. 2 is a front view.

FIG. 3 is a rear view.

FIG. 4 is a left side view.

FIG. 5 is a right side view.

FIG. 6 is a bottom view; and,

FIG. 7 is a top plan view.

The broken line showings throughout the views are for illustrative purposes only and form no part of the claimed design.
